(57) **CLAIM**

We claim the ornamental design for a canister, as shown and described.

DESCRIPTION

FIG. 1 is a first perspective view of a canister, showing our new design;

FIG. 2 is a second perspective view of the canister;

FIG. 3 is a third perspective view of the canister;

FIG. 4 is a fourth perspective view of the canister;

FIG. 5 is a front view of the canister;

FIG. 6 is a rear view of the canister; and,

FIG. 7 is a top view of the canister.

The broken lines in the drawings depict portions of the canister that form no part of the claimed design.
